UNITED STATES PATENT OFFICE.

WILLARD O. LATHROP, OF CINCINNATI, OHIO.

SPRING-BED SUPPORTING-HANGER.

1,209,175.

Specification of Letters Patent.

Patented Dec. 19, 1916.

Application filed November 3, 1914. Serial No. 870,137.

To all whom it may concern:

Be it known that I, WILLARD O. LATHROP, a citizen of the United States of America, and a resident of Cincinnati, in the county 5 of Hamilton and State of Ohio, have invented a certain new and useful Improvement in Spring-Bed Supporting-Hangers, of which the following is a specification.

This invention relates to hanger-supports 10 for spring bed-bottoms and its object is to provide in connection with the hanger-support and the spring-bed side-rail an arched clamp-plate that is longitudinally-mounted on the said side-rail and has a pair or more 15 of downwardly-turned corners that engage the said side-rail when it is placed in position to cap or span the inner end of the longitudinally-slotted hanger base or bar and is itself provided with a hole through 20 which a bolt passes upwardly from an aligned hole in said side-rail and the slot in said base or bar, and a suitable thumb-nut used to adjustably and detachably secure the plate and the hanger in the desired 25 relation on said side-rail to suit varied widths of bedsteads.

The device is a very simple one and is 30 fully described herein in connection with the accompanying sheet of drawings, in which—

Figure 1 is a perspective view showing one form of the improved hanger device in connection with sectional fragments of the bed-spring side-rail and the angle-bar or 35 side-rail of the bedstead; Fig. 2, a longitudinal section taken on the dotted-line a , a , of Fig. 1; Fig. 3, a perspective view similar to Fig. 1, but showing the clamp device in use in connection with a straight, flat bar 40 whose outer end rests on the lower inner shoulder or ledge of a wooden side-rail; and Fig. 4, a perspective view of the preferred 45 form of clamp-plate having a single pair of pendent or downwardly-turned corners at but one longitudinal side only.

1 indicates an angle-iron side-rail of a bedstead shown in Fig. 1 with its horizontal side turned inwardly toward the spring-bed side-rail 2 which parallels it and is also 50 of a similar right-angle-iron form (as seen in both Figs. 1 and 3). The side-rail 1 is of somewhat heavier material than that of the side-rail 2, as customary, and my invention is adapted for use in connection 55 with a wooden side-rail 1 that has the usual

shoulder or ledge 3 along its inner lower edge (as seen in Fig. 3 only).

When a right-angle bar or angle-iron is used for the bedstead side-rail 1 (as seen in Figs. 1 and 2), a common form of hanger 60 composed of a vertical main-member 4, upper horizontal hook-member 5 and lower horizontal base-member or foot 6, is best adapted for engagement therewith and for supporting the spring-bed structure there- 65 from. A longitudinal slot 7 is pierced in the base or foot 6 of the hanger to provide for bedsteads of varied widths. When a wooden bedstead side-rail is used, however, a straight, horizontal bar 6^a is necessary, the 70 same being slotted at 7 like unto the foot 6 of the angled hanger. In order to couple the said hangers to the side-rail of the spring-bed for suspending or supporting the latter between the usual pair of side- 75 rails 1 of the bedstead, I provide a clamping-plate that is composed of a body portion 8 having downwardly-turned flanges 9, 9, at its opposite ends, bases or feet 10 projecting from said flanges, and downwardly-turned 80 arms or stops 11 preferably at one end only of each of the bases or feet 10, along one longitudinal edge or side of the clamping-plate (as seen in Fig. 4 only). The arms or stops 11 can, however, be provided at 85 both ends of both of the bases or feet 10, which would locate them at each of the four corners of the rectangular clamping-plate (as seen in Figs. 1, 2 and 3), but it would not be essential to do so, as the two stops 90 11 seen in Fig. 4 will be ample to keep the plate from turning or shifting on the side-rail 2 when once set and secured in place. Besides, the use of but the two stops 11, seen in Fig. 4, renders the device more readily and cheaply made, and, also, more readily handled in manufacture, packing and use.

A vertical bolt 12 is used to attach each hanger to the side-rail 2 of the spring-bed. 100 This bolt has its shank extended upwardly through a circular hole 13 in the horizontal upper member of the angle-iron forming said side-rail 2, thence through the slot 7 in the hanger base or foot 6 (or bar 6^a, as 105 the case may be), thence through a central hole 14 pierced in the body portion 8 of the clamping-plate to be finally capped or engaged by a nut (thumb one, as shown, preferred) 15 on its upper screw-threaded 110

end. The lower end of the shank of the bolt is preferably square in cross-section to prevent its turning in the slot 7 when applying the fastening-nut 15, as ordinarily.

When the clamping-plate is in capping or coupling place, with its arched or raised body portion resting on the hanger base 6 (or bar 6^a), the opposite ends or feet 10 thereof are preferably elevated slightly above the top face of the angle-iron or side-rail 2 (as in Fig. 2) to secure a better frictional contact and clamping effect between the nut 15 and said top face of the side-rail 2, especially for the contiguous faces of the hanger base or bar 10 and the said top face of side-rail 2.

The arms 11 have sufficient depth to extend somewhat below the lower face of the upper horizontal member of the spring-bed 20 side-rail 2 so as to form ample stops to hold or interlock the clamping-plate in the proper square or alined relation with the hanger foot or bar and the side-rail 2.

I claim:—

25 In combination, a spring-bed angle-iron

Copies of this patent may be obtained for five cents each, by addressing the "Commissioner of Patents, Washington, D. C."

side-rail and a transverse supporting-hanger device, the latter comprising a longitudinally-slotted hanger-bar, a centrally-orificed clamping-plate having downwardly-turned opposite ends adapted to transversely seat 30 upon and span the said slotted hanger-bar at the slotted portion thereof, imperforate horizontal feet or flanges extending from said downwardly-turned opposite ends, short downwardly-turned stop-arms formed 35 at the opposite ends of the said horizontal flanges of the clamping-plate and adapted to freely span and engage said side-rail, a vertical bolt that is partly flat-sided and adapted to engage a circular hole in the 40 horizontal wing of the said side-rail, thence engaging the slot in said hanger-bar against turning and thence engaging the said central orifice of the clamping-plate, and a clamping-nut on the outer threaded-end of 45 the bolt.

WILLARD O. LATHROP.
